GENERATOR REGULATING DEVICE

Bennett M. Leece, Cleveland, Ohio, assignor to
 The Leece-Neville Company, Cleveland, Ohio,
 a corporation of Ohio

Application May 18, 1935, Serial No. 22,251

7 Claims. (Cl. 171—222)

This invention relates to the control of electric generators, and more particularly to regulators of the electro-magnetic vibratory type for maintaining the voltage of generators within desired limits.

An object of the present invention is to provide an improved voltage regulator of the electromagnetic vibratory type which is of simplified and economical construction and which operates with minimum arcing and wear at the contacts.

Another object of the invention is to provide an improved voltage regulator, of the type mentioned having a novel circuit arrangement rendering the same substantially universally applicable to all electric generators of a given class or rating.

A further object of the invention is to provide an improved voltage regulator, of the type referred to, having a novel arrangement of magnet coils and contacts whereby substantially full field excitation is had during starting of the generator, after which the field strength is automatically varied to maintain the terminal voltage at a predetermined value independently of changes in the speed and load of the generator.

Another object of the invention is to provide an improved voltage regulator, of the type having a plurality of contacts controlled by the vibratory armature of an electromagnet, and wherein the circuit connections for the contacts and the energizing coils of the magnet are such that the vibratory armature cooperates with one contact during starting of the generator, and thereafter cooperates with another contact to maintain the terminal voltage at a substantially constant value.

Still another object of this invention is to provide an improved voltage regulator, of the type above referred to, wherein the energizing winding of the electromagnet includes a voltage coil, and an auxiliary coil which either is short circuited or magnetically opposes the voltage coil during starting of the generator and subsequently magnetically assists the voltage coil.

It is a further object of this invention to provide an improved voltage regulator embodying a vibratory armature and an electromagnet having a voltage coil and an auxiliary coil, and wherein circuit connections controlled by the armature cause the auxiliary coil to be either short circuited or energized in opposition to the voltage coil during starting or low speed operation of the generator, and subsequently to be intermittently connected into the field circuit and at the same time energized in additive relation to the voltage

coil to thereby cause the armature to intermittently establish a field deenergizing circuit.

Other objects and advantages of the invention will be apparent from the following description when taken in conjunction with the accompanying sheet of drawings, wherein

Fig. 1 is a diagrammatic view illustrating the circuit arrangements of my improved voltage regulator;

Fig. 2 is a similar view illustrating another embodiment of my invention and

Fig. 3 is a diagrammatic view illustrating another form of my improved voltage regulator.

More detailed reference will now be made to the accompanying drawing for the purpose of describing my improved regulator which is especially applicable to variable speed, variable load generators of the type commonly used with the battery charging and lighting systems of motor vehicles. It will be understood of course that the invention may be embodied in various other regulators and regulating arrangements which come within the scope of the appended claims.

The present invention has to do particularly with vibratory regulators of the double contact type, and is an improvement over the regulators disclosed in my earlier application Ser. No. 674,008, filed June 2, 1933, and in my earlier application Serial No. 700,813, filed Dec. 4, 1933.

I have found that in the operation of voltage regulators it is desirable to have circuit connections which will afford substantially full field excitation for starting or low speed operation of the generator so that the terminal voltage will be quickly built up or maintained. It is also desirable to have the terminal voltage thereafter maintained at a substantially constant value, notwithstanding the occurrence of variations in the speed and load of the generator. In order that the regulator may be commercially practical and efficient and reliable in operation, it should be capable of accomplishing these ends with very little arcing or wear at the contacts. I find that these desired results can be best obtained by providing a double contact arrangement wherein the armature cooperates with one contact during starting of the generator and thereafter shifts over into vibratory cooperation with another contact for controlling circuits which maintain the terminal voltage at the desired constant value.

In Fig. 1 of the drawing I show a generator 10 which may be a third brush type of generator now commonly used on motor vehicles. As represented in the drawing the generator has main brushes 11 and 12, and a field winding 13 hav-

ing one end thereof connected to the third brush 14.

The voltage regulator 15 comprises an electro-magnet having a frame 16 with energizing coils 17 and 18 thereon. An armature 19 extends across the poles of the frame 16 and is mounted for vibratory movement under the influence of the magnetizing windings 17 and 18. The armature may be flexibly mounted on the frame by means of the resilient member 20, which also electrically connects the armature with the frame.

The regulator 15 is provided with circuit controlling contacts which may include an upper contact 22 and a lower contact 23 between which a portion of the vibratory armature 19 may extend. The armature may be provided with a contact 24 for cooperation with the contact 22 and a contact 25 for cooperation with the contact 23. Contacts 24 and 25 are electrically connected with the armature 19 and hence electrically connected with each other. A tension spring 26 has one end thereof connected with an anchor 27 and the other end connected with the armature 19 so as to normally urge the contact 24 into engagement with the contact 22.

The magnet coil 17 may be referred to as a voltage coil because its ends are connected respectively to the main brushes 11 and 12 of the generator. One end of this coil is connected with the main brush 11 through conductor 29, contact 22, and conductor 30 and the other end of this coil is connected with the main brush 12 through conductor 31. The coil 18 is an auxiliary or secondary magnet coil having one end thereof grounded on the frame 16 and its other end connected with the main brush 12 by the conductor 31. The auxiliary coil 18 is so wound and arranged with respect to the voltage coil 17 that when it is energized by current flowing therethrough in one direction, it magnetically opposes the voltage coil, and when energized by current flowing therethrough in the opposite direction, it magnetically assists the voltage coil.

It will be noted from Fig. 1 that the upper contact 22 is connected with the main brush 11 of the generator by the conductor 30 and that the lower contact 23 is connected with the main brush 12 of the generator through conductor 32 and conductor 31.

Load conductors such as the conductors 34 and 35 may be connected with the main brushes 11 and 12, or with the conductors 30 and 31 leading therefrom, for supplying current from the generator to various apparatus to be operated thereby. In this instance the load conductors 34 and 35 supply current to the clamps 36 and to the storage battery 37. A suitable switch or cutout 38 may be provided in a part of the load circuit such as in the conductor 34.

In the operation of the regulator arrangement just described let it be assumed that the generator 10 is being started from rest. At this time the contact 24 is held against the contact 22 by the spring 26 and, hence, the field winding 13 will be connected directly across the main brush 11 and the third brush 14, and as the generator begins to operate the field magnetization will build up rapidly. At this time the voltage coil 17, which is connected across the main brushes 11 and 12, will also be energized and will cause magnetization of the regulator frame 16. While the contacts 22 and 24 are closed, current will also travel from the main brush 11 through conductor 30, and through the armature and frame

of the regulator, and then through the auxiliary coil 18, and back to the main brush 12 through conductor 31. The flow of current through the circuit just traced energizes the coil 18 so as to magnetically oppose the voltage coil 17.

The resistance and number of turns of the coil 18 are of course selected in accordance with the functions which this coil is to perform in relation to the other parts of the apparatus, and with respect to the voltage coil 17, the coil 18 has relatively fewer ampere turns. For example, the coil 18 may have a value of 50 ampere turns and the voltage coil 17 may have a value of 200 ampere turns. Assuming that these coils have the values just mentioned, it will be seen that when the coil 18 magnetically opposes the coil 17, the combined value of two coils will be 150 ampere turns, and when the coil 18 magnetically assists the coil 17, the combined effect of the two coils will be 250 ampere turns.

As the speed of the generator builds up and the field strength increases, the terminal voltage will increase correspondingly. The building up of the generator speed will also cause an increase in the magnetization of the frame 16 as the result of the preponderance of the coil 17 over the then opposing coil 18. When the magnetization of the frame 16 increases to the point where the armature 19 is attracted against the action of the spring 26, and moves the contact 24 out of engagement with the contact 22, the circuit connections for the field winding 13 and the magnet coil 18 are changed. Upon the opening of the contacts 22 and 24 the magnet coil 18 is connected into the field circuit in series with the winding 13 and becomes a field resistor in addition to its function as a magnet coil.

The field circuit at this time may be traced from the main brush 11 through conductors 30 and 29, then through voltage coil 17, magnet coil 18, and through the frame and armature of the regulator, and then through field winding 13 back to field brush 14. The resistance of the magnet coils 17 and 18 now being inserted in the field circuit causes a decrease in the ampere turns of the field winding 13, as compared with the ampere turns of this winding when connected directly across the brushes 11 and 14, and hence causes a decrease in the rate at which the terminal voltage of the generator is building up.

The opening of the contacts 22 and 24 inserts the magnet coil 18 into the field circuit, as just explained, but it will be noted that the direction of current flow through this coil is in a direction opposite to what it was when the contacts 22 and 24 were closed, and instead of opposing the voltage coil 17 the coil 18 now assists the voltage coil. With the winding 18 assisting the voltage coil 17, the armature 19 will be attracted with increased force and will be shifted away from the contact 22 and toward the contact 23. As the terminal voltage continues to build up, the attraction on the armature 19 will increase correspondingly and the contact 25 will ultimately be moved into engagement with the contact 23, whereupon the energizing circuits for the field winding and the magnet coil 18 are again changed.

The closing of the contacts 25 and 23 causes the field winding 13 to be connected across the brushes 14 and 12, which results in a substantial deenergization of the field winding. The energizing circuit for the field winding now extends

from the third brush 14 through the field winding and through the armature of the regulator, and then through contacts 25 and 23, and conductors 31 and 32 to main brush 12. Since the outer end of the field winding is now connected with main brush 12 instead of main brush 11 there will be a tendency to reverse the flow of field current and this tendency will cause the field flux to be suddenly collapsed and the field 5 to be substantially deenergized. The closing of the contacts 25 and 23 also short circuits the auxiliary coil 18 of the regulator and the resulting deenergization of this coil causes a decrease in the total magnetization of the regulator frame. 10 The combined effect of the sudden deenergization of the field 13 and the decrease in the magnetization of the regulator frame by short circuiting the coil 18, allows the contacts 23 and 25 to be quickly opened by the spring 26. The opening of these contacts restores the field energizing circuit which includes the regulator coils 17 and 18, and thereupon the field strength again 15 builds up.

It will be understood of course that the operation of the regulator as just explained takes place with a very rapid vibratory movement of the armature 19. It will also be understood that by reason of the arrangement of the winding 18, the contact 24 will cooperate with the contact 22 only long enough to quickly build up the field strength and the terminal voltage of the generator during starting, and then the armature will shift over into cooperation with the contact 23. Thereafter the vibratory action of the armature 25 will cause rapid opening and closing of the contacts 23 and 25 to maintain the voltage substantially constant as explained above, without causing closing of the contacts 22 and 24.

In Fig. 2 of the drawing I have shown a regulator arrangement similar to that just explained, but wherein the circuits for the magnet coils 40 and 41 of the regulator 42 are somewhat different. In the arrangement of Fig. 2 the generator 43 is provided with a field winding 44 and with main brushes 45 and 46, and a third brush 47. The regulator 42 has upper and lower contacts 49 and 50 with which the contacts 51 and 52 of the regulator armature 53 cooperate under the influence of the action of the coils 40 and 41 and the tension spring 54.

The coil 41 of the regulator is the voltage coil and the coil 40 is an auxiliary coil arranged in additive relation to the voltage coil. One end of the coil 40 is grounded on the frame 55 of the regulator and its other end is connected with the main brush 45 through the conductors 56 and 57. The upper contact 49 is connected with the main brush by the conductor 57 and the lower contact 50 is connected with the main brush 46 by the conductor 58. The voltage coil 41 has one end connected with the main brush 45 through the conductors 56 and 57, and its other end connected with the main brush by the conductor 58.

When the contacts 49 and 51 are closed, such as when the generator is being started up, the field winding 44 is connected directly across the main brush 45 and third brush 47 and at this time the magnet coil 40 is short circuited by the conductor 56. When terminal voltage of the generator builds up and the armature 53 is attracted against the action of the spring 54, the opening of the contacts 49 and 51 causes the magnet coil 40 to be connected in series with the field winding 44. This coil now being energized, assists the voltage coil 41 and shifts the operation of

the armature 53 so that it will cooperate with contact 50 instead of contact 49. The field circuit at this time may be traced from main brush 45 through conductor 57, contact 49, conductor 56, magnet coil 40, and then through regulator frame and armature 53 and 53, and through field winding 44 to main brush 47.

As the terminal voltage of the generator continues to increase, the armature 53 will be attracted by the increased magnetization of the magnet frame 55 produced by the additive coils 40 and 41, and the contacts 52 and 50 will be closed. The closing of these contacts connects the outer end of the field winding 44 with the main brush 46 through the conductor 58 to cause a substantial collapse of field flux and deenergization of the field winding in the manner explained above. A corresponding decrease occurs in the terminal voltage of the generator and allows the contacts 50 and 52 to be quickly opened by the spring 54. The opening of the contacts restores the field energizing circuit which includes the coil 40, and the field flux again builds up.

During the operation of the regulator, as just explained, it should be understood that the armature 53 moves with a very rapid vibratory action during the closing and opening of the contacts 52 and 50.

In Fig. 3 of the drawing, I have shown a regulator arrangement which is identical with that of Fig. 1, with the exception that a resistor 60 is connected between the armature of the regulator and the upper contact. Since the arrangement of Fig. 3 is otherwise identical with that of Fig. 1, I have used primed reference characters in Fig. 3 to designate the corresponding parts. The resistance 60 may or may not be employed, but when used tends to reduce arcing across the contacts. This resistance also serves as an auxiliary load resistor across the main brushes 11' and 12' when the contacts 23' and 25' are closed.

From the foregoing description and the accompanying drawing it will now be seen that I have provided improved regulator arrangements for controlling the voltage of electric generators and maintaining the terminal voltage at a desired predetermined value. It will also be seen that in the regulator arrangements which I have provided, an auxiliary magnet coil either opposes the voltage coil of the regulator or is short circuited while the generator is being started up and subsequently assists the voltage coil in causing the field circuit to be altered to produce the desired regulating action. With the arrangement which I have disclosed it will be seen furthermore, that the coils of the regulator exert maximum effectiveness in altering or controlling the field circuit in such manner as to cause the field to be quickly collapsed or built up, the result of which is to maintain the terminal voltage at the desired predetermined value by opening and closing only one pair of contacts. With the arrangements which I have disclosed, a very rapid vibratory movement of the armature is obtained with minimum sparking and wear at the contacts.

Having thus described my invention, I claim:

1. In combination, a generator having brushes and a field winding, a regulator comprising a magnet having energizing coils and a vibratory armature adapted to be actuated by the magnet, a pair of contacts adapted to be closed by said armature to connect the field winding across

- brushes of the generator, a second pair of contacts adapted to be intermittently closed and opened by vibration of the armature, said energizing coils including a voltage coil and an auxiliary coil, circuit connections for substantially deenergizing the field winding when the second pair of contacts is closed, and circuit connections for energizing said auxiliary coil in magnetically opposed relation to said voltage coil when the first mentioned pair of contacts is closed.

2. In combination, a generator having brushes and a field winding, a regulator comprising a magnet having energizing coils and a vibratory armature adapted to be actuated by the magnet, a pair of contacts adapted to be closed by said armature to connect the field winding across brushes of the generator, a second pair of contacts adapted to be intermittently closed and opened by vibration of the armature, said energizing coils including a voltage coil and an auxiliary coil, circuit connections for substantially deenergizing the field winding when the second pair of contacts is closed, and circuit connections for energizing said auxiliary coil in magnetically opposed relation to said voltage coil when the first mentioned pair of contacts is closed and in additive relation to the voltage coil when said first mentioned pair of contacts is open.

3. In combination, a generator having brushes and a field winding, a regulator comprising a magnet having energizing coils and a vibratory armature adapted to be actuated by the magnet, a pair of contacts adapted to be closed by said armature to connect the field winding across brushes of the generator, a second pair of contacts adapted to be intermittently closed and opened by vibration of the armature, said energizing coils including a voltage coil and an auxiliary coil, circuit connections for substantially deenergizing the field winding when the second pair of contacts is closed, and circuit connections for energizing said auxiliary coil in magnetically opposed relation to said voltage coil when the first mentioned pair of contacts is closed, and in additive relation to the voltage coil and in series with the field winding whenever both pairs of contacts are open.

4. In combination, a generator having brushes and a field winding, a regulator comprising a magnet having energizing coils and a vibratory armature adapted to be actuated by the magnet, a pair of contacts adapted to be closed by said armature to connect the field winding across brushes of the generator, a second pair of contacts adapted to be intermittently closed and opened by vibration of the armature, said energizing coils including a voltage coil and an auxiliary coil, circuit connections for substantially deenergizing the field winding when the second pair of contacts is closed, and circuit connections for energizing said auxiliary coil in magnetically opposed relation to said voltage coil when the first mentioned pair of contacts is closed and to substantially deenergize said auxiliary coil when the second pair of contacts is closed.

5. In combination, a generator having brushes including a pair of main brushes and a third brush and a field winding with one end thereof connected with the third brush, a regulator comprising a magnet having energizing coils and a vibratory armature adapted to be actuated by the magnet, a pair of spaced contacts, contact means carried by the armature for cooperation with the contacts of said pair, said field winding having its other end connected with the contact means of the armature, the energizing coils of the magnet including a voltage coil and an auxiliary coil having one end connected with one main brush and its other end connected with the contact means of the armature, means connecting one contact of said pair with said one main brush and the other contact of said pair with the other main brush, and a spring acting on said armature to bias the contact means thereof toward said one contact of said pair, said auxiliary coil being energized to magnetically oppose the voltage coil when the contact means of the armature engages said one contact of said pair.

6. In combination, a generator having brushes including a pair of main brushes and a third brush and a field winding with one end thereof connected with the third brush, a regulator comprising a magnet having energizing coils and a vibratory armature adapted to be actuated by the magnet, a pair of spaced contacts, contact means carried by the armature for cooperation with the contacts of said pair, said field winding having its other end connected with the contact means of the armature, the energizing coils of the magnet including a voltage coil and an auxiliary coil having one end connected with one main brush and its other end connected with the contact means of the armature, means connecting one contact of said pair with said one main brush and the other contact of said pair with the other main brush, and a spring acting on said armature to bias the contact means thereof toward said one contact of said pair, said auxiliary coil being arranged to magnetically oppose the voltage coil when the contact means of the armature engages said one contact of said pair and to magnetically assist the voltage coil when the contact means of the armature moves away from the said one contact of said pair.

7. In combination, a generator having a field winding, a regulator comprising a magnet having energizing coils and a vibratory armature adapted to be actuated by the magnet, a circuit for the field winding including a resistor, a pair of contacts adapted to be closed by said armature for short-circuiting said resistance out of the field circuit, a second pair of contacts adapted to be closed by said armature, said energizing coils including a voltage coil and an auxiliary coil, and circuit connections controlled by said pairs of contacts for connecting said resistance into an auxiliary load circuit of the generator when the second pair of contacts is closed and for energizing said auxiliary coil to magnetically oppose the voltage coil when the first pair of contacts is closed and to magnetically assist the voltage coil when the first pair of contacts is open.

BENNETT M. LEECE.
